UNITED STATES PATENT OFFICE.

LUCIEN PIERCE, OF MALDEN, MASSACHUSETTS.

MACHINE FOR LABELING CYLINDRICAL PACKAGES.

Application filed October 4, 1919. Serial No. 328,394.

To all whom it may concern:

Be it known that I, LUCIEN PIERCE, a citizen of the United States, residing at Malden, county of Middlesex, State of Massachusetts, have invented an Improvement in Machines for Labeling Cylindrical Packages, of which the following description, in connection with the accompanying drawing, is a specification, like characters on 10 the drawing representing like parts.

This invention relates to improvements in labeling machines and the object thereof is to provide a machine which will automatically apply a label to a receptacle, such 15 as a can or carton.

In labeling machines heretofore constructed, the label is usually coated with an adhesive throughout its entire area, and is applied to the receptacle while in a moistened 20 condition. In thus applying labels they are sometimes stretched or wrinkled and present an undesirable appearance.

One of the objects of the present invention is to provide a means for attaching the label 25 to the carton by an adhesive applied along the edge of the carton ends or covers or adjacent the ends of the receptacle. Where cartons are employed which have covers for their ends, the label when thus applied will 30 serve to secure the covers upon the cartons and also to substantially seal the same hermetically.

While a label thus secured at its edges to the ends or covers of a receptacle may be 35 sufficient, it is usually desirable to have the ends of the label also fastened to the carton, and a further object of the invention is to provide means for securing one end of the label directly to the carton longitudinally 40 of the latter, and also for causing the other end of the label to overlap the end thus secured, the overlapping end being pasted down. By thus applying a label to a carton only a small portion of its surface is effected by the moisture of the adhesive, and consequently the label when applied retains 45 its original brilliancy, is free from wrinkles, and presents a more desirable appearance than the labels applied in the usual manner.

A further object of the invention is to provide an automatic machine comprising a travelling carrier having a series of receptacle holding members which may be operated to grip the receptacle and through a 50 part of the travelling movement to rotate the receptacle, means being provided for

applying an adhesive to the moving receptacle, and further means being provided for presenting one end of the label to the adhesive thus applied, so that the rotation of 60 the receptacle will cause the label to be wrapped about it.

A further object of the invention is to provide a label holding device which will present one end of the label to the bands of adhesive upon the receptacle and will progressively release the label as it is being wrapped around the receptacle.

Another object of the invention is to provide a novel feeding mechanism for delivering 70 the receptacles to the travelling carrier.

Another object of the invention is to provide a means for applying circumferential bands of adhesive to the receptacle adjacent its ends before it is presented to the travelling carrier.

Another feature of the invention consists in providing a transerrer for positioning the receptacles in the path of the rotatable 80 holders on the travelling carrier, the transerrer preferably having a movement in synchronism with that of the carrier while this receptacle is being gripped by the holders on the latter.

Another object of the invention is to provide a novel means for actuating the holders of the travelling carrier to cause them to automatically grip the receptacle, and after 85 the label has been applied to release the same.

Another object of the invention is to provide means for supporting the tanks which hold the adhesive in such a manner that they can be readily removed so that they may be transported to a humid room or chamber 95 when not in use in order to prevent a hardening of the adhesive.

Other objects and features of the invention will more fully appear from the following description and the accompanying drawings, and will be particularly pointed out in the claims.

The drawings illustrate a preferred embodiment of my invention which is adapted to apply labels to cylindrical receptacles, such 105 as cartons or cans, but it will be understood that the invention may be adapted to apply labels to receptacles of other forms within the meaning and scope of the claims herein.

In the drawings—
Fig. 1 is a side elevation of a labeling machine embodying my invention.

Fig. 2 is an elevation of the opposite side of the machine than that illustrated in Fig. 1, the greater portion of the frame being broken away and certain of the parts illustrated in section.

Fig. 3 is a detail view of the mechanism for applying bands of adhesive to the end portions of the receptacle, and for transferring the receptacle to the travelling carrier, the receptacle being shown in the position in which it is about to be delivered from the adhesive applying device to the trans- 10 ferrer which positions it in the path of the holders of the travelling carrier.

Fig. 4 is a view of the same mechanism illustrating in full lines one receptacle in the position in which the bands of adhesive are being applied to it, another receptacle in 15 the trans- ferrer, and showing in dotted lines 20 the mechanism in position to transfer the receptacle to the holders of the travelling carrier.

Fig. 5 is a detail view, in longitudinal section, of a portion of the label and paste 25 tank holder.

Fig. 6 is a vertical section view trans- versely of the label holder on line 6—6 Fig. 5.

Fig. 7 is a vertical sectional view through 30 one side of the label holder illustrating the supporting instrumentalities or fingers for sustaining a pile of labels.

Fig. 8 is a similar view illustrating one 35 label supporting instrumentality or finger withdrawn to release the lowermost label of the pile.

Fig. 9 is a detail plan view of the receptacle holders of the travelling carrier showing a mechanism for actuating same to grip 40 and release the receptacle.

Fig. 10 is a detail view in vertical section of one of the receptacle holding chucks and parts of the mechanism by which it is actuated.

Fig. 11 is a detail view partly in section 45 illustrating a modified form of the invention in which frictional means are employed to rotate the receptacles when the labels are being applied,

Fig. 12 is a transverse sectional view on lines 12—12 Fig. 11, viewed from the left,

Fig. 13 is a detail longitudinal sectional view of the spiders and their telescopically mounted heads showing the main shaft in 50 elevation.

The labeling machine which comprises my 60 invention may be stated broadly to consist of a traveling carrier which may be of any form, but as illustrated herein, is in the form of a rotatable spider having a series of receptacle holders or chucks which are adapted to be rotated during a portion of the traveling movement of the carrier, means being provided for applying an adhesive to 65 the receptacle either before it is placed in

the holder of the traveling carrier, or during the time it is being carried by said carrier, or both. The invention also contem- 70 plates presenting the end of a label to the adhesive upon the rotating receptacle so that the rotation of the receptacle will wrap the label around it.

In the preferred embodiment of the invention shown herein, the label thus presented is the lowermost one of a pile of 75 labels carried in a suitable holder, and the holder is provided with means for successively releasing the supported portions of the label as it is wrapped about the receptacle.

The label holder also is preferably pro- 80 vided with an adhesive container upon which the under side of the lowermost label rests so that when the label is wrapped around the receptacle the overlapping portion will be pasted upon the end which is first applied to the receptacle.

The labeling machine illustrated in the accompanying drawings comprises a frame having skeleton sides 1, comprising horizontal webs 2, in the center portion of which is a journal 3, for a main shaft 4 to which spiders 5, 6 are secured.

These spiders may be secured permanently to the shaft as indicated in Fig. 2 and preferably are adjustably mounted thereon to permit the machine to be adapted for receptacles of different lengths. In the latter case the spiders 5 and 6 desirably are pro- 95 vided with extended hubs 5^a and 6^a which are telescopically arranged and slidably mounted upon the shaft 4. They may be adjustably secured together and to the shaft 4 by suitable set screws as shown in Fig. 13.

The shaft 4 is rotated through a gear 7 105 which is secured to it and meshes with the pinion 8 upon a driving shaft 9, which like the shaft 4 is journaled in suitable bearings carried by the transverse web 2 of the main frame. The driving shaft 9 is provided 110 with the usual fast and loose driving pulleys.

The arms of the spiders 5 and 6 desirably are bifurcated at their ends and provided 115 with bosses 5^x and 6^x which form bearings for the shafts of rotatable receptacle holders, which, as illustrated herein are in the form of cylindrical chucks and means are provided for causing the chucks which are carried by the arms of the spider 5 normally 120 to approach complementary chucks carried by the arms of the spider 6 in such a manner as to hold a receptacle between them while permitting the receptacle to be rotated.

Means are also provided for successively separating the chucks after the labels have been applied to the cartons in order to dis- 125 charge the receptacles and to permit the introduction of new unlabelled receptacles.

- In the preferred mechanism for accomplishing this purpose illustrated in detail in Fig. 9 each of the arms of the spider 5 is provided with a journal in which the stem 5 of a chuck 10 is slidably mounted. A chuck plate 10^a preferably is detachably secured to the chuck 10 so that plates of different diameter may be applied to the chucks to correspond to receptacles of different size.
- 10 A shaft 11 which is screwed at one end into the chuck 10 extends axially therefrom and has at its opposite end an enlarged head 11^a which serves as an abutment for a cam 12 which is rotatably mounted upon 15 said shaft. The face of the cam 12 engages a complementary cam face upon the boss 13 which desirably is integral with and forms a part of the bifurcated end of the spider arm and provides a bearing for the shaft 20 11. A helical compression spring 14 surrounding the shaft 11 and inclosed in recesses in the boss 13 and in the stem of the chuck 10 tends normally to force the chuck away from the spider arm so that it will 25 co-operate with its companion chuck, which is carried by an arm of the spider 6, to engage the ends of the receptacle and rotatively support the same.

The cam 12 is provided with an extension 30 16 which carries a roller 17 which is adapted to engage a suitable cam track to withdraw the chuck from receptacle engaging position. The extension 16 of the cam 12 desirably is provided with a curved face 35 tending backwardly from the roller 17 which is adapted to engage the end of the cam track when the roller passes from the cam track and gradually to permit the chuck to be forced by the spring 14 against the 40 end of the receptacle during the rotation of the spiders.

A gear 15 located between the bifurcated portions of the end of the spider arm 5 is feathered to the stem of the chuck and is 45 adapted to be rotated by suitable means such as a toothed rack in a manner which will hereinafter be described.

The stems 18 of chucks 19 are journaled in the bifurcated ends of spider arms 6 50 which are companions to the arms of the spider 5. The chucks 19 like the chuck 10 are provided with detachable chuck faces 19^a which may be replaced by other chuck faces to fit different sizes of receptacles.

55 In view of the mechanism provided for causing the chucks 10 to move toward and from the companion chucks 19 there is no need for the chucks 19 to have endwise movement, so they are merely rotatably mounted in the ends of their respective arms and are only rotated when the receptacle is clamped between them and the chuck 10, and the chuck 10 rotated.

Longitudinal movement of the chuck stem 60 10 is effected through a cam track 20 which

is carried by a bracket 21 depending from the frame, which cam track lies in the path of the roller 17, so that as the carrier travels in the direction indicated by the arrow in Fig. 1 the cam 12 will be rotated upon its 70 shaft 11 and will draw the shaft endwise against the force of the spring 14 thus separating the chucks 10 and 19 sufficiently to allow the receptacle to be placed between them. 75

When the receptacle has been placed between them by the mechanism which will hereinafter be described the roller rides off of the end of the cam track 20, thus permitting the spring 14 to force the chuck 10 80 toward the chuck 19 until it engages one end of the receptacle and forces the other end firmly into engagement with the chuck 19. When the roller reaches the cam track the curved face of the extension 16 rides 85 against the roller carried by the end of the cam track and thereby restrains the endwise movement of the shaft 11 which is under the influence of the spring 14, causing the chuck 10 gradually to approach and engage the end of the receptacle instead of snapping against it as would be the case 90 in the absence of the curved face of the cam extension.

After the receptacle has thus been clasped 95 it is presented by the traveling carrier to means for applying adhesive lengthwise of the receptacle. The receptacle is then carried beneath a label holder which is actuated to present a label to it in such a manner 100 that the label will be engaged by the adhesive on the receptacle either by the adhesive bands at the ends of the receptacle or the strip or band of adhesive which extends longitudinally of the receptacle or 105 both.

In the meantime, as the receptacle approaches the label it is given an axial rotation so that when the label is engaged by the adhesive upon the receptacle it is automatically wrapped around the receptacle as the latter is carried forward during its rotation by the traveling carrier. 110

As illustrated in Fig. 2 the rotative movement is imparted to the receptacle by the 115 engagement of the teeth of the gear 15 with a series of pins carried by an arcuate member 22 mounted upon the main frame of the machine; but other means may be employed to accomplish this purpose, such as the frictional mechanism illustrated in Figs. 10 and 11 which will hereinafter be described. 120

One of the principal features of the invention consists in applying bands of adhesive peripherally around the receptacle 125 near its ends and in order to accomplish this, I have provided a preliminary mechanism which rotates the receptacle and applies the bands of adhesive thereto before the receptacle is delivered to the traveling carrier. 130

As shown in Figs. 1 and 2 the receptacles, which are cylindrical in form, are placed upon a chute 23 which has at its lower end an escapement adapted to release one receptacle at a time. The escapement which is illustrated in Fig. 2 comprises a bell crank 24, which is pivotally mounted upon studs 24^x carried by brackets upon the sides of the chute and has a finger 25 adapted to engage and hold the receptacle. The bell crank lever 24 is pivotally connected to the end of a lever 26 which is fulcrumed on a bracket 26^x and is actuated in properly timed relation by a cam 27 carried by a shaft 28 which is driven from the main shaft 9 through the medium of a sprocket and sprocket chain.

Beneath the end of the chute 23 a pair of rotatable adhesive applying disks 29 are rotated, said disks being carried by a shaft 30 which is journaled in brackets 31 and is rotated by a suitable train of gearing, as is illustrated in Fig. 1, or in any other suitable manner. The brackets 31 are removably secured to the end of the main frame of bolts 32. An adhesive receptacle is secured to the brackets 31 by fastening devices 34, which may be easily released so that the receptacle can be readily removed and transported to a humid chamber when not in use.

At the lower end of the chute a rotatable member is provided, which is illustrated herein in the form of a cylinder having a segmental recess 36, the recess being shaped to conform to the contour of the receptacle to which the label is to be applied. The rotatable member 35 is driven through suitable gearing in timed relation with the escapement which releases the lowermost receptacle and permits it to be engaged by the adhesive applying disks. In the operation of the machine the cam 27 actuates the escapement to release the lowermost receptacle upon the chute which then rolls down in contact with the periphery of the adhesive applying disks 29. The rotatable member 35 being in the path of the receptacle arrests it, and holds the receptacle between its periphery and the periphery of the rotating adhesive applying disks and assists in its rotation until the receptacle has completed at least one full rotation, and bands of adhesive have been applied to it adjacent its ends. The rotation of the member 35 at this point brings the recess 36 into the path of the receptacle so that the latter drops into said recess, and upon further rotation of the member 35, is carried away from the adhesive applying disks and delivered to a transerrer which in turn delivers the receptacle to the chucks of the traveling carrier.

The transerrer is employed in order to position the receptacles properly in the path of the chucks when the latter is actuated to grip the ends of the receptacle and prefer-

ably the transerrer has a movement in synchronism with the movement of the carrier, thus enabling the carrier to have a continuous movement, instead of an intermittent movement which in other labeling machines has been found necessary to enable the receptacles to be placed in the chucks. The transerrer which is illustrated herein comprises a cradle 37 having a recess 38 to fit the receptacles, said cradle being carried by arms 39 which are pivotally mounted upon the main shaft 4. The outer end of one of the arms 39 rests upon a cam 40 which is mounted upon the shaft 28 and is positioned in timed relation with the other portions of the mechanism. The cam 40 is so constructed that the cradle, after having received the receptacle, will be raised at the same rate of movement as the movement of the chucks on the arms of the traveling carrier. This is possible by reason of the fact that the cradle is carried by arms which are pivoted upon the same shaft as that which carries the spider of the traveling carrier. During the time the cradle is moving in unison with the spider arms and chucks, the roller 17 of the cam 12 runs off of the end of the track 20 and permits the chuck 10 to engage one end of the receptacle and press its opposite end firmly against the complementary chuck 19. When the receptacle has thus been grasped, the cam 40 permits the arm which carries the cradle 37 to drop into position to receive the next succeeding receptacle.

The receptacles when thus held in the rotatable chucks upon the traveling carrier are ready to be presented to the label applying mechanism. It is, however, desirable that the ends of the labels as well as the edges be secured to the receptacle, and in order to accomplish this, an adhesive applying device is located in the path of the receptacle before the latter is presented to the label applying mechanism.

The means for applying a longitudinal band of adhesive to the receptacle which is illustrated herein comprises an adhesive applying roller 41 which is mounted upon a shaft carried by journals 42 which are adjustably mounted in obliquely disposed ways in a bracket 43. The bracket 43 is also provided with journals for a roller 44 the lower portion of which is immersed in an adhesive contained in a tank 45. Suitable means are provided for rotating the rollers 41 and 43 so that the roller 43 will be caused to deliver the adhesive to the adhesive applying roller 41 thereby enabling the adhesive to be transferred by the roller 41 to the receptacles as they successively engage the periphery of the roller 41.

By adjusting the roller 41 toward and from the roller 44 the thickness of the film of adhesive which is transferred to the receptacles may be varied in accordance with the

requirements of the receptacles being labelled.

In order to adapt the machine for different sizes of cartons the adhesive applying mechanism is adjustably supported so that it can be moved toward and from the path of the traveling carrier. This is accomplished in the present construction by providing the receptacle 45 with a bracket 46 having an adjusting screw 46^x which engages a transverse member of the main frame of the machine. By this means for adjusting the tank the roller 41 which is carried upon the tank may be positioned accurately in respect to the path of the periphery of the receptacles being labelled and adjustment made for receptacles of different diameters.

It is desirable that the adhesive tank and rollers shall be so supported that they can be conveniently removed from the machine and supported in a moist chamber which will prevent the drying of the adhesive when it is necessary to stop the operation of the machine. In the present construction the tank 45 is supported upon arms 47 which are provided at their upper ends with hooks 48 which engage a transverse bar or shaft 49. By reason of this construction the adhesive tank and rollers can be removed together by merely lifting the tank sufficiently to detach the hooks 48 from the support 49.

It will be obvious that when the receptacle has been clamped between the chucks and carried upwardly by the traveling carrier, its surface will come in contact with the periphery of the adhesive roller 41 and a band of adhesive will be smeared upon the receptacle longitudinally of its axis. The receptacle therefore is then ready for the label to be applied. Upon further movement of the traveling carrier the gear, 15 as illustrated in Figs. 1 and 2, will engage the pins or teeth upon the arcuate member 22 and cause the rotation of the receptacle holding chucks, and consequently the receptacle. Shortly after the receptacle thus commences to rotate the end of the label is presented to it and the further rotative and traveling movement of the receptacle serves to wrap the label around it. A preferred mechanism for thus applying the label comprises a label holder, which as shown herein, is in the form of a rectangular frame having sides 50 and ends 51. The ends 51 preferably are formed of adjustable sections which may be secured together by bolt and slot connections as illustrated in Figs. 5 and 6, to permit the use of labels of different widths. The rear end of the label holder is pivotally mounted upon the shaft 52 which is journaled in suitable bearings in brackets 53, extending upwardly from the frame of the machine. The front end of the label holder rests upon the end 54 of a lever 55 which is pivoted upon a stud shaft 56 in a link 57 which is adjustably se-

cured by a bolt and slot connection 58 to a bracket 59 extending upwardly from the frame of the machine.

The bracket 59 also is provided with an extension 60 upon which a shaft 61 is journaled. The shaft 61 has upon it a sprocket wheel 62 which is driven by the main sprocket chain which is driven from the driving shaft 9 of the machine. The shaft 61 has fixed upon it a cam 63 which engages a roller 64 at the opposite end of the lever 55. The cam is so constructed and timed in its rotation as to permit the front end of the label holder to descend and present the front, reverse or lower side of the lowermost label to the adhesive which has previously been applied to the receptacle. The label will thus adhere at its end to the receptacle, and the further rotation of the receptacle during the traveling movement will cause the label to be wrapped around the receptacle.

In order that the lowermost label alone may be delivered, a special means has been provided for releasing successive portions of the label as the receptacle is carried along beneath it. The means for supporting the label comprises a series of instrumentalities such as L-shaped fingers 65 which are supported upon pivots 66 and are provided with lateral extensions 67 which are connected by helical springs 68 to a stationary portion of the side members 50 of the label holder. These fingers are normally held in horizontal position, as illustrated in Fig. 7 by cams 69 upon shafts 70 which extend along the sides of the label holder, and are driven by suitable gears through a sprocket chain which is actuated by a sprocket on the main shaft, the timing of the rotation of the shaft 70 being of course in synchronism with the rotation of the main shaft and with that of the rotating receptacle holders. The cams 69 for actuating the successive fingers 65 are so positioned that when the receptacle approaches the front end of the label and the label holder is depressed to present the lowermost receptacle, the first finger will be removed and the end of the label will be free to engage the adhesive on the receptacle. As the rotating receptacle travels along, the successive cams 69 release the supporting fingers 65 which are then withdrawn by their springs so that the label will be freed properly. As soon as the portion 110 of the label which is being wrapped upon the receptacle has passed beyond a withdrawn finger the finger is returned by its cam to the horizontal or supporting position. Thus, the lowermost labels in the pile 120 are successively delivered to the receptacles carried by the successive spider arms.

In order to apply adhesive to the rear end of the label which overlaps the end which has been fastened to the receptacle, I have so 130

constructed the label holder that the lowermost label will rest upon a paste reservoir as shown in Fig. 5. The paste reservoir 71 preferably is carried by one or both the 5 side pieces 50 of the label holder, and is provided with a forward bottom extension 72 which forms a ledge upon which the ends of the labels rest. The upper edge of the ledge is provided with grooves or serrations 73 which will permit a sufficient amount of paste to adhere to the label to 10 secure properly the overlapping end of the label in place.

In order to provide for the adjustment of 15 the label holder to accommodate labels of different widths the extension 72 may be so constructed as to extend laterally beneath one of the sides 50 of the label holder and provided with a thin cover which will close 20 the serrations 73 which are not engaged by the end of the lowermost label in the pile.

While the labels may be wrapped around the receptacles or cartons in the manner above described without further mechanism, it is desirable to provide means for 25 pressing the labels firmly down upon the receptacle as they are being wrapped around it. To accomplish this purpose each pair of spider arms carries arms 74 supporting at their outer ends a roller 75 adapted to engage the periphery of the receptacle carried between the chucks 10 and 19. The arms 74 preferably are formed integral with a hollow hub or sleeve 74^a which is pivotally 30 mounted upon studs 74^b which project toward each other from the arms of the spider. These studs are of sufficient length to permit the spiders to be separated when cans of different length are being operated 35 upon without detaching the hub 74^a which carries the arms 74 and the smoothing roller 75. One of the arms 74 of each pair is in the form of a lever which is connected at 40 its inner end to a link 76 which has a bayonet slot 77, which receives a guiding stud 78 projecting from the spider arm. The link 76 also has a lateral extension or tail 79 which is adapted to be engaged by a cam track 80 carried by the frame of the machine. In the normal operation of the machine, the arms swing away from the receptacle holding chucks and are held in such a position by the stud entering the laterally 50 extended portion of the bayonet slot. When, however, the rotating receptacle holding members have reached the point at which the end of the label has been presented and applied, the cam track 80 engages the tail 79 of the link 76 and causes it to oscillate 55 sufficiently to press the roller 75 firmly into engagement with the end of the label which is being applied to the rotating receptacle. Upon further movement of the carrier a roller 81 which is carried by a stud which

forms the pivot between the arms 74 and 65 the link 76 engages a track 82 which is pivotally mounted upon a stud 82^a projecting from the frame of the machine. The weight of the track is sufficient to hold the roller 75 not firmly but yieldably in engagement 70 with the label and is of such length as to retain the roller in label engaging position until it has passed over the entire length of the label and smoothed it down upon the receptacle. The track 82 is provided with 75 a downwardly extending bracket 83 upon the lower end of which a complementary track 84 is pivoted. A spring 85 connected to the track 82 and to the complementary track 84 normally tends to throw the track 80 84 toward the track 82 so that it engages the roller 81 as said roller passes along the track 82. When the roller passes from the end of the track 82 the spring 85 causes the track 84 to throw the roller outwardly thereby actuating the lever 74 to remove the roller 75 from engagement with the receptacle and causing the link 76 to slide upon the pin 78 until said pin enters the lateral recess of the bayonet slot and thereby retains the arm 74 in inoperative position until the tail 79 of the link 76 is again engaged by the cam 80.

After the label has thus been applied means are provided for releasing the receptacle. A preferred means shown in the drawing comprises a track 86 secured to the web 2 of the main frame and carrying a stud 87 which lies in the path of the extension 16 of the cam 12 upon the chuck 100 shaft so that as the arms of the traveling carrier move downwardly the engagement of said extension with the stud will rotate the cam in the reverse direction, thereby removing the chuck 10 from engagement 105 with the receptacle and permitting the same to drop upon a suitable chute 88.

Any suitable means may be provided for driving the various mechanisms above described. In order however, to maintain the 110 parts in proper synchronism I have found it convenient to drive practically all of the mechanisms from a single sprocket chain 89 which passes over a sprocket gear 90 upon the driving shaft, thence over a 115 sprocket wheel 91 on the shaft 61 which carries the cam for actuating the label holder, thence over the sprocket wheel 92 upon the shaft 49 which also carries a sprocket driving a chain 93 for rotating the adhesive applying roller 41, thence over a sprocket 94 which actuates the adhesive applying disks and also the transerrer, thus it will be seen that all the essential parts of the mechanism are maintained in properly timed relation.

Instead of employing positively engaging means for rotating the receptacle car-

rying chucks, frictionally engaging members may be used and a convenient and desirable mechanism of this character is illustrated in Fig. 10 in which the arms of 5 the spider 5 are shown as carrying chucks 10 such as above described and the chuck shafts are rotated by disks 100 which frictionally engage a track 101 supported from a segment 102 by brackets 103 having stop 10 screws 104 to limit the outward movement of the track 101. The track 101 is pressed against the peripheries of the disks 100 by springs 105 which are inclosed in sleeves 106 carried by brackets 107 extending up- 15 wardly from the segment 102. The lower end of the springs 105 is seated upon the outer edge of the track 101 and may be compressed to any desired extent by an adjusting screw 108 carried by the sleeves 20 106. While but two brackets carrying compression springs are illustrated, any desired number may be used as will be readily understood.

In the operation of the machine a number of receptacles or cartons are placed in 25 the chute 23. Upon starting the machine the escapement is actuated to release the lowermost receptacle in the chute so that it rolls down over the adhesive applying rollers 29 until it engages the cylindrical periphery of the rotatable member 35 which arrests it and in co-operation with the rotating disks 29 revolves the receptacle thus enabling the disks to apply bands of adhesive circumferentially adjacent the ends 30 of the receptacle. The receptacle then drops into the recess 36 of the rotatable member 35 and is delivered by it to the cradle 37 of the transerrer. As the receptacle holding members upon the travelling carrier approach the receptacle held in 35 the cradle, the cam 40 raises the cradle supporting arms so that the cradle moves in unison with the movement of the receptacle 40 holding members or chucks.

Prior to and during the time the cradle is thus moving and before it has reached 45 transferring position the roller 17 in the extension of the cam 12 has engaged the cam track 20 and actuated the cam to withdraw the chuck 10 away from its companion chuck 19 so that the receptacle can enter 50 between them then as the cradle moves in unison with the chuck the roller 17 on the extension of the cam rides from the end of the track 20 and permits the spring 14 to force the chuck 10 against one end of the receptacle, thus forcing the other end 55 against the chuck 19 and clamping the receptacle between said chucks. The cam 40 then permits the cradle to drop back into inoperative position.

As the traveling carrier with the receptacle grasped between the chucks advances 60 65 the receptacle is brought into engagement

with the adhesive applying roller 41 which deposits a band or strip of adhesive longitudinally of the body of the receptacle. Upon further progressive movement of the carrier the gears 15 engage the pins upon 70 the rack 22 (or the friction disks 100 engage the friction track 101 of the arcuate member 102) thereby causing the chucks to rotate the receptacle.

During this rotation the labels are presented to the receptacles by the depression of the label holder so that the front end of the lowermost label engages the adhesive which has been applied to the receptacle and the rotation of the receptacle during its 80 advancing movement wraps the label about the receptacle.

The label is smoothly rolled down upon the receptacle by the action of the roller 75 and when the operation is completed the receptacle is finally released from the chucks and falls upon the discharge chute 88.

It will be understood that the embodiment of the invention disclosed herein is illustrative and not restrictive and that various changes may be made in construction and arrangement of parts within the meaning and scope of the following claims.

Having thus described my invention what I claim as new and desire to secure by Letters Patent is—

1. A machine for applying labels to receptacles comprising means for applying circumferential bands of adhesive around the receptacle closely adjacent its ends, a travelling carrier having rotatable means operable to engage the ends of the adhesive-banded receptacle, and means for progressively applying a label from one of its ends to the other to said receptacle during its travelling and rotating movement, and means for progressively pressing the label firmly in contact with said receptacle during its application thereto.

2. A labeling machine for applying labels to cylindrical receptacles comprising means for applying circumferential bands of adhesive around the receptacle adjacent its ends, a travelling carrier having rotatable means operable to engage the ends of the adhesive-banded receptacle, means for applying a strip of adhesive lengthwise of the receptacle between said bands of adhesive, means for presenting one end portion of a label to the strip of adhesive, and means for progressively pressing the label against the receptacle whereby it will be smoothly attached and secured at its end and edges to the receptacle.

3. A labeling machine for applying labels to cylindrical receptacles comprising means for applying circumferential bands of adhesive around the receptacle adjacent its ends, a travelling receptacle-holding means, means for transferring the adhesive-banded

- receptacle thereto, means for applying a strip of adhesive lengthwise of the receptacle between said bands of adhesive, means for presenting one end portion of a label to 5 the strip of adhesive, and means for applying a strip of adhesive to the other end of the label, means for progressively pressing the label against the receptacle from the end which is presented to the strip of adhesive on the receptacle to the other end whereby the label will be smoothly stretched and secured at both its ends and both its edges to the receptacle.
4. A machine for applying labels to receptacles comprising a travelling carrier having a series of receptacle holding means, means for applying adhesive to said receptacle during its travelling movement, means for rotating the receptacle during the travelling movement of said carrier, a label holder carrying a pile of labels, means for reciprocating said label holder to cause the same to present one end of an exposed label of the pile to the adhesive coated surface of the 20 travelling rotating receptacle, and means carried by said travelling carrier operating to progressively press the label in contact with said receptacle, whereby said label will be wrapped about the receptacle during its further travelling rotating movement.
5. A machine for applying labels to receptacles comprising a travelling carrier having a series of receptacle holding means, means for applying adhesive to said receptacle during its travelling movement, means for rotating the receptacle during the travelling movement of said carrier, a label holder carrying a pile of labels, means for reciprocating said label holder to cause the same 25 to present one end of an exposed label of the pile to the adhesive coated surface of the travelling rotating receptacle, and means for applying a narrow band of adhesive to the opposite end portion of said label whereby said label will be wrapped about the receptacle during its further travelling rotating movement.
6. A machine for applying labels to receptacles comprising a travelling carrier having a series of receptacle holding means, means for applying adhesive to said receptacle during its travelling movement, means for rotating the same during the travelling 30 movement of said carrier, a label holder having a series of supporting members carrying a pile of superposed labels located above the path of said travelling receptacles, means for reciprocating said label holder to cause the same to present one end of the lowermost label to the adhesive coated surface of the travelling rotating receptacle, and means for actuating said supporting members to release said lowermost label whereby
- said label will be wrapped about the receptacle and secured thereto during its further rotating travelling movement.
7. A machine for applying labels to receptacles comprising a travelling carrier having a series of pairs of rotatable chucks, 70 means for presenting receptacles to said chucks, means for actuating said chucks to cause them to engage opposite ends of said receptacles, means for rotating said chucks after having engaged said receptacles, means for applying an adhesive successively to the bodies of said receptacles during their travelling movement, means for presenting labels successively to the adhesive-coated surfaces of said receptacles during their travelling rotating movement and means for releasing the lowermost label whereby the labels will be wrapped around and secured to them and means for releasing the labeled receptacles from said chucks. 80
8. A machine for applying labels to receptacles comprising means for applying circumferential bands of adhesive to said receptacle, a travelling carrier having a series of receptacle holding means, means for successively actuating said receptacle holding means to grip a receptacle, means for rotating the receptacle holding means, means for presenting the receptacle to the receptacle holding means including a trans- 90 ferrer adapted to receive said receptacle from said adhesive applying means, means for moving said transerrer in synchronism with said receptacle holding means during the time the latter is actuated to grip the receptacle and means for applying the labels to the rotating receptacle. 95
9. A machine for applying labels to receptacles comprising a traveling carrier having a series of receptacle holding means, 105 means for successively actuating said receptacle holding means to grip a receptacle, means for rotating the receptacle holding means, means for presenting the receptacle to said receptacle holding means, including a pivotally supported cradle adapted to receive said receptacle and means for moving said cradle in synchronism with said receptacle holding means during the time the latter is actuated to grip the receptacle, and 110 means for applying the labels to the rotating receptacles. 115
10. A machine for applying labels to receptacles comprising a traveling carrier having a series of rotatable receptacle holding means, means for successively feeding receptacles to said holding means including an escapement operating to deliver the receptacles one at a time, and means intermediate of said escapement and said receptacle holding means for applying adhesive to said receptacles. 120
11. A machine for applying labels to re-

- ceptacles comprising a traveling carrier having a series of rotatable receptacle holding means, means for successively feeding receptacles to said holding means including 5 an escapement operating to deliver the receptacles one at a time and means intermediate of said escapement and said receptacle holding means for rotating said receptacle and applying circumferential bands of 10 adhesive thereto.
12. A machine for applying labels to receptacles comprising a traveling carrier having a series of rotatable receptacle holding means, means for successively feeding receptacles to said holding means including an 15 escapement operating to deliver the receptacles one at a time and means intermediate of said escapement and said receptacle holding means for rotating said receptacle and 20 applying circumferential bands of adhesive thereto, including a rotatable adhesive applying member having its periphery partially immersed in the adhesive and a cooperating traveling member engaging the 25 periphery of the receptacle.
13. A machine for applying labels to receptacles comprising a traveling carrier having a series of receptacle holding means, means for successively actuating said holding 30 means to grip a receptacle, a transerrer for positioning the receptacles in the path of said holding means, a rotatable adhesive applying means, and a traveling member cooperating therewith to apply a peripheral 35 band of adhesive to said receptacle, and having means for delivering the receptacle to said transerrer.
14. A machine for applying labels to receptacles comprising a traveling carrier having a series of receptacle holding means, means for successively actuating said holding 40 means to grip a receptacle, a transerrer for positioning the receptacles in the path of said holding means, a rotatable adhesive applying means, a cylindrical rotatable member located adjacent to said adhesive 45 applying means and cooperating therewith to rotate the receptacle, said cylindrical member having a recess to receive the receptacle and operating to deliver the receptacle to the transerrer.
15. A machine for applying labels to receptacles comprising a traveling carrier having a series of receptacle holding means, 50 means for successively actuating said holding means to grip a receptacle, a transerrer for positioning the receptacles in the path of said holding means, a rotatable adhesive applying means comprising a pair of rotatable disks having their peripheries partially submerged in an adhesive and positioned to apply bands of adhesive to the receptacle adjacent its ends, a cooperating rotatable cylinder having a recess, operable first to 55 rotate the receptacle while the adhesive is being applied and thereafter to deliver the receptacle to the transerrer.
16. A machine for applying labels to cylindrical receptacles comprising a feeding chute adapted to receive a series of receptacles, an 60 escapement acting intermittently to release the lowermost receptacle in said chute, rotatable means for applying bands of adhesive adjacent the ends of said receptacles, a cooperating rotatable cylindrical member having a recess in its periphery operating in conjunction with said adhesive applying means to rotate the receptacle while the adhesive is being applied and thereafter to 65 deliver the receptacle, a transerrer to receive said receptacle, a traveling carrier having a series of rotatable receptacle holding means operating successively to grip the ends of the receptacles, and means for applying labels to the adhesive bearing receptacles.
17. A machine for applying labels to cylindrical receptacles comprising a feeding chute adapted to receive a series of receptacles, an escapement acting intermittently 70 to release the lowermost receptacle in said chute, rotatable means for applying bands of adhesive adjacent the ends of said receptacles, a cooperating rotatable cylindrical member having a recess in its periphery operating in conjunction with said adhesive applying means to rotate the receptacle while the adhesive is being applied and thereafter to 75 deliver the receptacle, a transerrer to receive said receptacle, a traveling carrier having a series of rotatable receptacle holding means operating successively to grip the ends of the receptacles, and means for applying labels to the adhesive bearing receptacles.
18. A machine for applying labels to cylindrical receptacles comprising a feeding chute adapted to receive a series of receptacles, an escapement acting intermittently 80 to release the lowermost receptacle in said chute, rotatable means for applying bands of adhesive adjacent the ends of said receptacles, a cooperating rotatable cylindrical member having a recess in its periphery operating in conjunction with said adhesive applying means to rotate the receptacle while the adhesive is being applied and thereafter to 85 deliver the receptacle, a transerrer to receive said receptacle, a traveling carrier having a series of rotatable receptacle holding means operating successively to grip the ends of the receptacles, and means for applying labels to the adhesive bearing receptacles.
19. A machine for applying labels to cylindrical receptacles comprising a feeding chute adapted to receive a series of receptacles, an escapement acting intermittently 90 to release the lowermost receptacle in said chute, rotatable means for applying bands of adhesive adjacent the ends of said receptacles, a cooperating rotatable cylindrical member having a recess in its periphery operating in conjunction with said adhesive applying means to rotate the receptacle while the adhesive is being applied and thereafter to 95 deliver the receptacle, a transerrer to receive said receptacle, a traveling carrier having a series of rotatable receptacle holding means operating successively to grip the ends of the receptacles, and means for applying labels to the adhesive bearing receptacles.
20. A machine for applying labels to cylindrical receptacles comprising a feeding chute adapted to receive a series of receptacles, an escapement acting intermittently 100 to release the lowermost receptacle in said chute, rotatable means for applying bands of adhesive adjacent the ends of said receptacles, a cooperating rotatable cylindrical member having a recess in its periphery operating in conjunction with said adhesive applying means to rotate the receptacle while the adhesive is being applied and thereafter to 105 deliver the receptacle, a transerrer to receive said receptacle, a traveling carrier having a series of rotatable receptacle holding means operating successively to grip the ends of the receptacles, and means for applying labels to the adhesive bearing receptacles.
21. A machine for applying labels to cylindrical receptacles comprising a feeding chute adapted to receive a series of receptacles, an escapement acting intermittently 110 to release the lowermost receptacle in said chute, rotatable means for applying bands of adhesive adjacent the ends of said receptacles, a cooperating rotatable cylindrical member having a recess in its periphery operating in conjunction with said adhesive applying means to rotate the receptacle while the adhesive is being applied and thereafter to 115 deliver the receptacle, a transerrer to receive said receptacle, a traveling carrier having a series of rotatable receptacle holding means operating successively to grip the ends of the receptacles, and means for applying labels to the adhesive bearing receptacles.
22. A machine for applying labels to cylindrical receptacles comprising a feeding chute adapted to receive a series of receptacles, an escapement acting intermittently 120 to release the lowermost receptacle in said chute, rotatable means for applying bands of adhesive adjacent the ends of said receptacles, a cooperating rotatable cylindrical member having a recess in its periphery operating in conjunction with said adhesive applying means to rotate the receptacle while the adhesive is being applied and thereafter to 125 deliver the receptacle, a transerrer to receive said receptacle, a traveling carrier having a series of rotatable receptacle holding means operating successively to grip the ends of the receptacles, and means for applying labels to the adhesive bearing receptacles.

- means for applying a strip of adhesive longitudinally of each receptacle while in said carrier, means for presenting the end portion of a label to said longitudinal strip of adhesive, smoothing rollers mounted upon said traveling carrier and means for causing said rollers to press the labels firmly upon the peripheries of said receptacles.
19. A machine for applying labels to receptacles comprising a traveling carrier having a series of rotatable receptacle holding means, and means for applying an adhesive to said traveling receptacles including a roller partially immersed in adhesive and yieldably supported to engage successive receptacles, means for rotating said receptacles and means for presenting labels successively to the receptacles.
20. A machine for applying labels to receptacles comprising a traveling carrier having a series of rotatable receptacle holding means, and means for applying an adhesive to said traveling receptacles including a roller partially immersed in adhesive and means pivotally supporting said roller positioned to cause said roller to engage successive receptacles, means for rotating said receptacles after the adhesive has been applied and means for presenting labels to the receptacles whereby the labels will be wrapped about the rotating receptacles.
21. A machine for applying labels to receptacles comprising a traveling carrier having a series of rotatable receptacle holding means, means for applying an adhesive to said traveling receptacles including an adhesive tank, a roller partially immersed in the adhesive in said tank, means for pivotally supporting said tank to cause said roller to lie in the path of the traveling receptacles, said pivotal supporting means being detachable to permit said tank to be removed from the machine in order that it may be placed in a humid chamber to prevent drying of the adhesive when not in use.
22. A machine for applying labels to receptacles comprising a main shaft and means for rotating the same, a pair of spiders mounted on said main shaft and spaced apart, pairs of complementary chucks having shafts journalled in said spiders, adapted to engage the ends of a receptacle, means for rotating said chuck shafts during a portion of their traveling movement, means for applying adhesive to the periphery of the receptacles, and means mounted upon said spiders operating while the labels are being wrapped around the receptacles to press the labels firmly and smoothly in contact with the peripheries of said receptacles.
23. A machine for applying labels to receptacles comprising a main shaft and means for rotating the same, a pair of spiders mounted on said main shaft and spaced apart, pairs of complementary chucks having shafts journalled in said spiders, adapted to engage the ends of a receptacle, means for rotating said chuck shafts during a portion of their traveling movement, means for applying adhesive to the periphery of the receptacles, and means mounted upon said spiders operating while the labels are being wrapped around the receptacles to press the labels firmly and smoothly in contact with the peripheries of said receptacles.
24. A machine for applying labels to receptacles comprising a traveling carrier having pairs of complementary rotatable holders adapted to engage receptacles, means to rotate said holders and means to apply labels to said traveling rotating holders, smoothing rollers carried by arms pivotally mounted upon said traveling carrier, means normally holding said rollers out of contact with said receptacles and means for oscillating said roller carrying arms to cause the smoothing rollers to engage the labels and press them firmly against the peripheries of said receptacles while the labels are being wrapped around said receptacles.
25. A machine for applying labels to receptacles comprising a traveling carrier having pairs of complementary rotatable holders adapted to engage receptacles, means to rotate said holders and means to apply labels to said traveling rotating receptacles, smoothing rollers carried by arms pivotally mounted upon said traveling carrier, links connected to said arms having bayonet slots, means on said carrier engaging said bayonet slots and acting normally to hold said rollers out of contact with the receptacles and means for engaging and actuating said links to cause said arms to press the smoothing rollers against the labels while they are being wrapped around the receptacles.
26. A machine for applying labels to receptacles comprising a traveling carrier, a pair of complementary chucks provided with faces adapted to engage the ends of a receptacle, and having shafts journalled in said traveling carrier, one of said chuck shafts being movable longitudinally, a spring acting to hold the movable chuck normally in receptacle engaging position, and means including a cam mounted on said travelling carrier and co-operating stationary means for actuating said cam to withdraw the movable chuck from engaging position to discharge the labeled can.
27. A machine for applying labels to receptacles comprising a traveling carrier, having a series of rotatable receptacle holding means, and means for rotating the same, a holder for a pile of superposed labels, positioned above said traveling carrier and having a series of supporting instrumentalities engaging the lowermost label, means for suc-

- cessively removing said supporting instrumentalities as the rotating traveling receptacles pass beneath the same.
28. A machine for applying labels to receptacles comprising traveling carriers having a series of rotatable receptacle holding means and means for holding or rotating the same, a holder for a pile of labels having a series of pivotally mounted fingers engaging the lowermost label, means for actuating said label holder to present the front end of the lowermost label to the rotating traveling receptacle, spring actuated means tending to remove said fingers from supporting position and a cam shaft having cams normally acting to hold said fingers in supporting position but operating during the rotation of the cam shaft to release successively said fingers whereby the label will be progressively released from its front end toward the rear and wrapped upon the rotating receptacle.
29. A machine for applying labels to receptacles comprising a label holder having an adhesive receptacle provided with an extension adapted to support one end of a pile of labels with the adhesive in said extension in contact with the underside of the lowermost label and means for presenting and transferring successively the lowermost label to a traveling rotating receptacle.
30. A machine for applying labels to re-
- ceptacles comprising a label holder having an adhesive receptacle provided with an extension adapted to support one end of a pile of labels with the adhesive in said extension in contact with the underside of the lowermost label and means for presenting and transferring successively the lowermost label to a traveling rotating receptacle, 35 and means for adjusting the width 40 of said label holder.
31. A machine for applying labels comprising a traveling carrier consisting of a shaft having a pair of spiders carrying cooperating rotatable receptacle engaging 45 chucks, means for adjusting said spiders toward and from each other to accomodate receptacles of different lengths and means for presenting and applying labels to the receptacles held in said chucks. 50
32. A machine for applying labels comprising a traveling carrier consisting of a shaft having a pair of spiders provided with telescoping hubs adjustably mounted thereon, said spiders having arms provided with 55 rotatable receptacle engaging chucks, and means for presenting and applying labels to receptacles supported by said chucks.

In testimony whereof, I have signed my name to this specification.

LUCIEN PIERCE.
